UNITED STATES PATENT OFFICE.

RAYMOND BARRIER, OF LUBBOCK, TEXAS.

DESIGN FOR A TRADING STAMP.

Application filed March 20, 1924. Serial No. 9,004. Term of patent 7 years.

To all whom it may concern:

Be it known that I, RAYMOND BARRIER, a citizen of the United States, residing at Lubbock, in the county of Lubbock and State of Texas, have invented a new, original, and ornamental Design for Trading Stamps, of which the following is a specification, reference being had to the accompanying drawing, forming part thereof.

The figure is a face view of a trading stamp, showing my new design.

I claim:

The ornamental design for a trading stamp, as shown.

RAYMOND BARRIER.
